DESIGN FOR A FLATIRON

Arthur Illsche and Arthur Drummond, Rye, N. Y.

Application August 27, 1936, Serial No. 64,596

Term of patent 7 years

To all whom it may concern:

Be it known that we, Arthur Illsche and Arthur Drummond, citizens of the United States and residents of Rye, in the county of Westchester and State of New York, have invented a new, original, and ornamental Design for a Flatiron, of which the following is a specification, reference being had to the accompanying drawing, forming part thereof.

In the drawing—

Fig. 1 is a side elevational view of a flatiron showing our new design; and

Fig. 2 is a top plan view thereof.

The dominant feature of our design resides in the portion shown in full lines.

We claim:

The ornamental design for a flatiron as shown and described.

ARTHUR ILLSCHE.
ARTHUR DRUMMOND.
